A. W. MILLS.
PNEUMATIC AGITATOR AND CLEANER.
APPLICATION FILED OCT. 2, 1912.

By his Attorney,

Inventor:

Albert W. Mills,

J. A. Richards

UNITED STATES PATENT OFFICE.

ALBERT W. MILLS, OF WEST ORANGE, NEW JERSEY.

PNEUMATIC AGITATOR AND CLEANER.

1,078,512.

Specification of Letters Patent.

Patented Nov. 11, 1913.

Application filed October 2, 1912. Serial No. 723,470.

To all whom it may concern:

Be it known that I, ALBERT W. MILLS, a citizen of the United States, residing at West Orange, in the county of Essex and State of New Jersey, have invented certain new and useful Improvements in Pneumatic Agitators and Cleaners, of which the following is a specification.

The object of my invention is to provide an effective pneumatic agitator and cleaner, operative by alternate blowing and suction, to dislodge and agitate and to suck up and convey away small scraps of paper and other debris lodged in confined spaces, such as those in monotype machines for which no efficient mode of cleaning was known prior to my present invention, because the currents induced by suction apparatus do not agitate the air and debris lodged in the pockets and corners, and mere blowers only move the debris about and pack it into inaccessible corners. I have found the most effective apparatus for such purposes to be one like my present invention, which may be generally described as a manually-controlled blowing and suction-inducing agitator and cleaner, comprising a bent pipe having one end formed into an oblong nozzle, a manually-operated valve at the other end controlling discharge ports in connection with a dirt-bag or other debris-disposal means and an intermediate ejector discharging toward the valve and connected with a source of compressed air. When the valve is closed the only outlet for air supplied by the ejector of the tube is through its nozzle and the tool is a blower agitator. When the valve is opened the air from the ejector, including that induced from the nozzle is discharged into the dust bag, the air being allowed to escape and the debris retained.

In the accompanying drawings, showing one embodiment of my invention, Figure 1 is a section through the device, certain parts being shown in elevation; Fig. 2 is a fragmentary section on the line 2—2 of Fig. 1; Fig. 3 is a plan view of the valve adjusting means; and, Fig. 4 is a partial projection from Fig. 1 of the nozzle end of the device. My preferred apparatus for the above described uses comprises a bent tube 6, one limb 7, of which terminates in an oblong nozzle 8—which is most conveniently usable if disposed, as illustrated, with its long axis substantially in the same plane with the tube 6, while its long limb has an open end and

a port, 19, communicating with a dirt-bag or debris-disposal means 23, and an opposite circumferential slot 24; an angularly-movable tubular valve 17 fitting into, by its open inner end communicating with, and by its head 16 closing the open end of, the tube 6, and provided with a discharge port 18 adapted to be rotated with said valve into and out of register with the port 19 in the tube 6, and a valve stem 25, by which said valve can be rotated and is fixed against axial motion, said stem 25 being illustrated as engaging a tapped hole 26 in the valve extending through the slot 24 and terminating in a suitable head; and a compressed air pipe 12 having, adjacent to the valve 15, a hose nipple or other convenient means for attaching a compressed air pipe, and thence extending to and making a return bend 9 beyond, and a tight joint 10 with, the tube 6 and extending in the same to an ejector 11 directed toward the valve 17. The air pipe 12 is secured to the tube 6 by straps 13, 14, or other suitable means.

Enveloping the port 19 in the tube 6 and united therewith, I provide a threaded union 20; and a corresponding nut 21 is provided that has a conical portion 22, to which is secured the mouth of a suitable receptacle, such as a bag 23 of fabric that will serve to confine the dust but permit escape of air. The nut 21 will serve to detachably secure the bag to the ring 20.

The operation of my agitator and cleaner follows:—Compressed air is piped to the air pipe 12. The operator grasps the apparatus by the tube 6 and pipe 12 as a handle, inserts the nozzle 8 into the place to be cleaned, and rapidly manipulates the valve-stem 25 to alternately register and unregister the valve port 18 and tube port 19. When said ports are separated, the nozzle 8 is the only outlet for the air supplied through the ejector 11 and the apparatus acts as an agitator and the blast from said nozzle loosens, detaches and sets in motion the debris it is desired to remove; and instantly reversing the valve 17 and bringing the ports 18 and 19 into register, they become the air outlet because the air discharge from the nozzle is directed toward them; and said discharge draws along with it the air in the tube limb 7 and nozzle 8, causes suction, and draws into the nozzle the debris previously loosened and agitated.

It will be seen that the entire device is

comparatively small and light, and can be readily grasped by the hand, being connected with a source of fluid pressure by the usual rubber hose and a small bag can be 5 employed so that the device will not occupy very much space, and can be simply grasped in one hand and the nozzle or inlet end 8 inserted in any desired place for sucking in the dust and material desired to be removed; 10 and the contracted nozzle, being parallel with the plane of the tubes, can be inserted into small spaces. My device is especially designed for use as a dirt-agitator and 15 cleaner with machines known as the mono-cleaner type, and similar apparatus.

Having thus described my invention, I claim:

1. A pneumatic agitator and cleaner comprising debris-disposal means, a tube having 20 an open end and a port in said tube adjacent to its opposite end and communicating with said disposal means, a rotatable tubular valve at said opposite end fitting in, and communicating with, said tube by one open 25 end, a head in said valve closing its outer end, a port being formed in said valve adapted by rotation thereof to be registered with and separated from the port in said tube, and an air ejector in said tube adapted 30 to discharge toward said valve and to be 35 connected with a compressed air supply.

2. A pneumatic agitator and cleaner comprising debris-disposal means, a tube having 35 an open end and a port in said tube adjacent to its opposite end and communicating with

said disposal means, a rotatable tubular valve at said opposite end and fitting in, and communicating with, said tube by one open end, a head in said valve closing its outer end, a port being formed in said valve 40 adapted by rotation thereof to be registered with and separated from the port in said tube, a compressed air pipe attached to said tube, a hose nipple on said pipe, an air ejector connected therewith located within said 45 tube and adapted to discharge toward said tube and a threaded union enveloping the discharge port in said tube for attaching said disposal means, and, comprised in the latter, a union nut and dirt bag. 50

3. A pneumatic agitator and cleaner comprising debris-disposal means, a tube having an open end and a port in said tube adjacent to its opposite end and communicating with said disposal means, a circumferential 55 slot being formed in said tube, a rotatable tubular valve at said opposite end fitting in, and communicating with, said tube by one open end, a head in said valve closing its outer end, a valve-stem extending through said 60 slot, a port being formed in said valve adapted by rotation thereof to be registered with and separated from the port in said tube, and an air ejector in said tube adapted to discharge toward said valve and to be 65 connected with a compressed air supply.

ALBERT W. MILLS.
